FRANK L. MORGAN, OF WOODMONT, CONNECTICUT, ASSIGNOR TO UNDERWOOD TYPE-WRITER COMPANY, OF NEW YORK, N. Y., A CORPORATION OF DELAWARE.

TYPE-WRITING MACHINE.

1,280,274.

Specification of Letters Patent. Patented Oct. 1, 1918.

Application filed June 4, 1915. Serial No. 32,639.

To all whom it may concern:

Be it known that I, FRANK L. MORGAN, a citizen of the United States, residing in Woodmont, in the county of New Haven and State of Connecticut, have invented certain new and useful Improvements in Type-Writing Machines, of which the following is a specification.

This invention relates to typewriting machines which are especially constructed to facilitate the writing of bills, and simultaneously recording them, in a manner commonly known as "condensed charging"; a mechanism of this general nature being illustrated in the patent to W. H. Woodford, No. 923,749, granted June 1, 1909.

In the operation performed by the mechanism of the aforementioned patent, after the writing of a bill is completed, the platen is turned backward a considerable distance, the written bill withdrawn, another bill head inserted, and the platen then rotated forward to bring the proper part of the inserted bill head to the printing point. During these operations, the record sheet remains in the machine; and on the record sheet, the first line of writing on the new bill directly follows the last line of writing on the preceding bill, so that the necessity is avoided of leaving gaps between entries on the record sheet corresponding to the depth of heading on the printed bill heads. This special backward and forward rotation of the platen is usually effected by a crank 35 which rotates about the platen axis between stops provided upon the platen frame.

In practice, it has not been found always practicable to give the platen a backward throw sufficient to completely disengage the written bill from the platen. Yet, unless this is done, there is liability of disturbing the record sheet in removing the written bill. An object of the present invention is to provide means for expeditiously removing the 45 written bill without regard to the backward throw of the platen, and without possibility of disturbance of the record sheet. In effecting this object of the invention, advantage is taken of the adjustability of the 50 paper fingers longitudinally of the platen and relatively to the pressure rollers; features which are common to certain typewriting machines, for instance, the Underwood machine. By having the bill heads slightly 55 narrower than the record sheet, the latter

may be held by the paper fingers while the former are held only by the pressure rollers; so that, after a bill is written, if the pressure of the pressure rollers be relieved, the bill may be drawn out of the front of the 60 machine without disturbing the record sheet which continues to be held by the paper fingers.

For simplification of the operation of exchanging the written bill for a new bill head, 65 and for the purpose of effecting the exchange with rapidity and at the cost of as little labor as possible, the platen, in the present invention, is given its backward drive by a motor, instead of by hand, as 70 heretofore. It is an object of the invention to have this motor-drive of the platen controlled by a key which is employed to relieve the pressure of the pressure rollers on the written bill; so that depression of this 75 key will release the written bill to permit it to be withdrawn in a forward direction before the platen is thrown back, and subsequent release of the key will cause the motor to act to throw the platen to position for 80 the insertion of the new bill head.

In the particular embodiment of the invention hereinafter described in detail, this key-controlled mechanism comprises an escapement, which, upon depression of the 85 key, acts to release the motor from a stop which normally stays the action thereof and causes the motor to be temporarily stayed by another stop; and, upon release of the key, releases the motor from the temporary stop, 90 to cause it, first to lock itself to the platen, and then to drive the platen. It is an object to have this key actuate the pressure rollers through the ordinary operating mechanism of the latter, but without positive connection to the latter, both in order to avoid duplication of parts, and in order that the pressure rollers may have their usual action 95 at times when the motor is not involved.

A feature of the invention is the connection of the motor to a crank such as found in the machine of the patent above referred to, so that the platen may be manually driven with the newly inserted bill head to printing position, and in this operation, may serve as a means for re-winding the motor. Another feature of the invention is an automatic locking of the crank in its normal inactive position to prevent displacement of the same during the writing 100 105 110

of a bill. It is a feature of the invention that, owing to the connection of the crank to the motor, the motor stop may serve as the lock for the crank.

5 Other features and advantages will hereinafter appear.

In the accompanying drawings,

Figure 1 is a fragmentary view in perspective, looking from the front right-hand corner of the machine, and showing the platen and attached mechanism in normal, or writing, position.

Fig. 2 is a view in end elevation, of the parts shown in Fig. 1, certain of the operative positions of the parts being shown in dotted lines.

Fig. 3 is a view similar to Fig. 2, except that the operating crank has been thrown from normal position to position for the introduction of a new bill head.

Fig. 4 is a detail view in end elevation showing the relative positions of the crank, pressure rollers and platen, at the time the written bill is being withdrawn.

25 Fig. 5 is an enlarged detail view in end elevation of certain of the parts shown in Fig. 1, normal position being indicated in full lines, and the bill-removing position being indicated in dotted lines.

30 Fig. 6 is a view similar to Fig. 5, except that the positions indicated are those successively assumed by the parts in returning to, and just before reaching, normal position.

35 Fig. 7 shows in perspective the several details of the mechanism, unassembled and spaced apart for clearness.

Fig. 8 is a fragmentary detail view in perspective showing the spring drum with 40 its stop, and the detent for holding and releasing the drum; the detent being shown in its two positions.

The platen 1 of an Underwood typewriting machine is rotatably mounted by means 45 of an axle 2 in the ends of the platen frame 3. The platen is provided with the usual finger wheels and line-space wheel (not shown), for feeding it. Mounted upon spindles 4 and 5 are pressure rollers 6 and 6^a for holding the paper to the platen. These 50 rollers may be mounted in the usual way on bell cranks 7 and 8, adapted to rock on a shaft 9. Between the opposing arms 10 and 10^a of the two bell cranks is another 55 rock shaft 11 having a flattened cut-away portion 12, against which the bell cranks are held by the leaf springs 12^a which hold the rollers to the platen. Fixed to the shaft 11 is an arm 13 connected to one end of a 60 link 14, the other end of which is attached to one arm of a lever 15, pivoted at 16 to the frame, and carrying on its other arm a finger piece 17. Depression of finger piece 17 causes the flattened portion 12 of shaft 65 11 to be turned so as to spread the opposing

arms 10 and 10^a of the bell cranks which carry the pressure rollers 6 and 6^a, thereby rocking those bell cranks against the action of springs 12^a, to withdraw the pressure rollers from the platen, (from Fig. 3 to 70 Fig. 4 position), to release the paper. The usual finger rolls 18 hold the record sheet to the platen at the top of the latter. In the operation of the present invention, the paper fingers 19 are adjusted longitudinally 75 of the supporting rail 19^a to positions in which they catch the record sheet near the edge thereof, without, however, catching the bill heads; the latter being of less width, and being held to the platen solely by the 80 pressure rollers 6 and 6^a.

Upon one end of the platen axle 2 is fixed a hub 20 of a wheel 21 having teeth 22 corresponding in number to the teeth of the line-space wheel. The wheel is rotated 85 by means of a pawl or dog 23, pivoted at 24 upon a crank 25, having a finger piece 26. The tooth 27 of the pawl is normally disengaged from the wheel 21, as shown in Fig. 5, to permit independent rotation of 90 the wheel and platen. A pin 28 projecting from the pawl 23 normally lies within a segmental recess 29 in an annular flange 30 of a disk 31, which latter is connected by a screw 32^a to a tie-rod 32, fixed to the platen 95 frame 3. The pin 28 normally overlies a trip or latch 33 formed upon the side of a small disk 34, having a pivot or stem 35 by means of which it is seated in a circular recess 36 in the fixed disk 31. The trip 100 disk 34 has a pin 39 to engage a slot 40 in the fixed disk 31, to limit the throw of the former, and hence of the latch or trip thereon. A spring 41 is coiled about the stem 35 and engages the pin 39 and the disk 105 31 to return the trip disk to normal position. The stem 35 is threaded to receive a nut 42 in the form of a cap to inclose the pin 39 and spring 41, and to hold the latch or trip mechanism in place.

When the crank 25 is swung forward, the pin 28 rides down the forward inclined edge 43 of the recess 29, and presses down upon the trip 33, causing the trip disk 34 to rock from full to dotted line (Fig. 5) position; 110 and the tooth 27 of the pawl 23 to engage a tooth 22 of the wheel 21. The pawl is thereafter held to the wheel 21 by engagement of the pin 28 with the under side of flange 30 of the disk 31, and rides along 115 this flange as the crank 25 continues its forward movement. As soon as the pin 28 leaves the recess 29, the trip is returned to normal position by the spring 41. Continued forward movement of the crank 25 120 causes the wheel 21, and with it the platen, to be rotated until the crank is arrested by an adjustable stop 44.

The stop 44, (see Fig. 7) is tubular, and 125 is carried by an annular plate 45 loosely 130

mounted on the platen shaft between the toothed wheel 21 and the fixed disk 31. In the form of a plunger within the tubular stop, and adapted to be projected beyond the 5 plate 45, is a pin 46 for setting the stop. A coil spring 47 within the tube holds the pin 46 normally projected, and when free to act, projects the pin. A button 48 serves as a means for withdrawing the pin into the 10 tube when the stop is to be set, thereby permitting the annular stop-carrying plate to be turned until the pin is brought into registration with any selected one of a series of holes 49, at line-space intervals around 15 the flange 30 of the disk 31; whereupon the pin 46 is released to the action of its spring 47, and the stop 44 is set.

After the new bill head has been positioned, the crank 25 is thrown rearwardly 20 to bring the bill to printing point. During this rearward movement, the pin 28 returns along the flange 30 of the fixed disk, holding the pawl 23 in engagement with the toothed wheel 21, and carrying with it the 25 platen. At this time, however, the trip 33 is again in full line (Fig. 5) position, and cannot yield upward because of the position of the stop pin 39 thereon at the end of its slot 40; so that the pawl 23, instead of 30 releasing the wheel 21 at the point at which it originally engaged it, passes under, and is held by the trip 33 in engagement with the wheel 21, until the trip has been passed by the pin 28, and until a lug or tooth 50 on 35 the pawl 23 strikes a trip formed by a spring 51, secured to the fixed disk 31 which causes the pawl to be swung upward around its pivot 24, disengaging the same from the toothed wheel 21, and causing pin 28 to re- 40 enter the recess 29 from which it started. A stop 52 secured to the fixed disk 31 finally arrests the crank 25 on its return movement, and determines the normal, or writing, position of the parts. It will be noted that the 45 trip 33 forms a switch by which the pawl 23, during its return movement, is directed away from the guiding surface 43, and is thereby operative to drive the platen through a greater distance during the return of the 50 driving crank 25 than during the forward throw of the crank. Suitable spacing is thus provided on the record sheet between the last entry of a bill and the first entry of the succeeding bill.

55 The operation of the crank 25 has been described as if it were entirely manual. It is a feature of the present invention, however, that the return of the platen when the written bill is removed, may be largely automatic. To this end, the crank 25 has attached thereto a bar 53, the other end of which is set between two retaining ears 54 on a cup casing 55 which forms the movable member of a spring drum mounted on 60 the platen shaft. The spring 56 of the drum

is attached at one end at 57 to the casing 55, and at its other end to a hub 58 on a disk 38, held fast to the frame by the screw 32^a which attaches it and the disk 31 to the tie-rod 32. The disk 38 lies against the 70 drum casing 55 to form with the latter a closed casing for the drum spring. Disk 38 is slightly spaced from disk 31 to provide room for the trip cap 42, and for the tie-rod attachment. The spring 56 is wound 75 when the crank 25 is in Fig. 5 position, and when released to action, operates through the drum 55 and bar 53, to throw forward the crank 25. Normally the drum is locked against action. The lock consists of a latch 80 59 in the form of a lever pivoted at 60 to the frame, one arm of the latch lever carrying a finger piece 61, another arm of the lever carrying a detent or stop 62 which, when the latch lever is in normal position, 85 lies in the path of a lug or shoulder 63 on the drum 55, and holds the latter against the action of the spring 56. After a bill has been written and is to be removed, the finger piece 61 is depressed. This lifts the detent 90 62 out of the way of the stop 63 and would cause the crank 25 and connected parts to be thrown until arrested by the adjustable stop 44, except that, on depression of the release lever, a second detent 62^a thereon, 95 which forms with the detent 62, a sort of escapement mechanism, is lifted into the path of the stop lug 63^a on the face of the drum casing 55. The stop lug 63^a is so positioned as to be engaged by the detent 62^a 100 immediately after the stop 63 has passed under, and by, the detent 62. Thus, upon depression of the finger piece 61, there is a slight movement of the spring drum, which is in effect a mere setting of the drum for 105 its real throw, which takes place when the pressure on the finger piece 61 is released.

Besides setting the drum, the finger piece 61, when depressed, operates to move the pressure rollers 6 and 6^a to relieve the pressure of the same on the platen, so that the written bill may be slipped out at the front of the platen. This movement of the pressure rollers is effected from the finger piece 61, simultaneously with the setting of the 115 drum spring, by means of a finger 65 on the lever 59. This finger, as shown in Fig. 1, is adapted, upon depression of the finger piece 61, to engage the lever 15 through which the pressure rollers are ordinarily released; 120 and the latter lever and its connected parts are thereby operated precisely as if operated from the finger piece 17, as heretofore described. While the pressure on the finger piece 61 is maintained, the written bill is 125 removed. During this removal, the paper fingers hold the record sheet; but, by reason of the shorter length of the bill head, do not engage the latter.

When the pressure is removed from the 130

finger piece 61, a spring 66, which is connected at one end to the lever 59 and at its other end to the platen frame 3, restores the lever 59 to normal position, thereby removing the 5 detent 62^a from in front of the stop 63^a. Detent 62 is also at the same time returned to the path of the stop 63, but is now behind the latter, so that the drum spring is free to throw the crank lever 25 until the latter strikes the adjustable stop 44. Pressure rollers 6 and 6^a are returned 10 to their operative position by springs 12^a simultaneously with movement of the lever 59 to release the drum, so that the rolls run on the platen while the latter is being rotated by the drum spring. The parts when 15 finally arrested by the stop 44 are in position for the insertion of the new bill head.

When the new bill head with its carbon 20 is in position to be engaged at its leading edge by the pressure rolls, the crank 25 is thrown manually back to bring them to printing position. In this movement, because of the connection 53, the drum member 25 55 is also returned to normal position, and the drum spring 56 thereby wound up. When, on the return movement, the stop 63 reaches the detent 62 on the release lever, the latter is cammed up by means of a cam face 30 67 thereon, and after passage thereby of the stop 63, drops again to its retaining position in front of the latter. It will be noted that the detent 62 in locking the drum, also, by reason of the connection of the drum to 35 the crank 25, locks the latter with its connected parts during the writing of the bill, and until the release lever is again operated.

Variations may be resorted to within the 40 scope of the invention, and portions of the improvements may be used without others.

Having thus described my invention, I claim:

1. In a typewriting machine, the combination with a revoluble platen; of a pressure device for holding the paper to the platen; means for relieving the pressure of said device on the platen to permit removal of a sheet; a driver for the platen; a motor and connections therefrom to said driver to 45 throw the platen in one direction; and means whereby, upon release of the pressure-relieving means, the driver and platen are automatically delivered to the action of said motor to position the platen for another sheet.

2. In a typewriting machine, the combination with a revoluble platen; of a pressure device for holding the paper to the platen; means for relieving the pressure of said device on the platen to permit removal of a sheet; a driver for the platen; a motor and connections therefrom to said driver to 60 throw the platen in one direction; means for setting the motor connections when the pressure-relieving device is operated; and

means for automatically delivering the driver and platen to the action of the motor when the pressure-relieving means is released.

3. In a typewriting machine, the combination with a revoluble platen; of a pressure device for holding the paper to the platen; means for relieving the pressure of said device on the platen to permit removal of a sheet; a driver for the platen; a motor and connections therefrom to said driver to throw the platen in one direction; means whereby, upon release of the pressure-relieving means, the driver and platen are automatically delivered to the action of said motor to position the platen for another sheet; and means whereby manual operation of the driver in the opposite direction, to bring the newly inserted sheet to printing position, causes power to be stored in the motor for succeeding power drives of the platen.

4. In a typewriting machine, the combination with a revoluble platen, of a pressure device for holding the paper to the platen; means for relieving the pressure of said device on the platen, to permit removal of a sheet; a driver for the platen; a spring drum; a connection from the drum to the driver; a stop on the drum; a detent connected to said pressure-relieving device and normally in the path of said drum stop to hold the drum inoperative, said detent being removed from the path of said drum stop when said pressure-relieving device is 100 operated; and a second detent on said pressure-relieving means which engages the drum after said drum stop has passed the first detent and which holds the drum until removed therefrom by the release of the 105 pressure relieving means, whereupon the drum is released to drive the platen to position for the insertion of another sheet.

5. In a typewriting machine, the combination with a revoluble platen, of a pressure device for holding the paper to the platen; means for relieving the pressure of said device on the platen, to permit removal of a sheet; a driver for the platen; a spring drum; a connection from the drum to the 110 driver; a stop on the drum; and a detent connected to said pressure-relieving device and normally in the path of said drum stop to hold the drum inoperative, said detent being removed from the path of said drum 115 stop when said pressure-relieving device is operated.

6. In a typewriting machine, the combination with a revoluble platen, of a pressure device for holding the paper to the platen; means for relieving the pressure of said device on the platen, to permit removal of a sheet; a driver for the platen; a spring drum; a connection from the drum to the 125 driver; and an escapement mechanism con- 130

5 nected to the pressure-relieving means whereby movement of the latter in one direction sets the drum for a drive of the platen, and operation of the pressure-relieving means in the other direction causes the escapement to release the drum and the platen to be thrown to a position for insertion of a sheet.

7. In a typewriting machine; a revolute 10 platen; pressure rollers and paper clutching fingers coöperating with the platen to hold paper to the latter, the pressure rollers being within the margins defined by the paper fingers so that the former may engage a bill 15 head or the like which is free from the latter, while the latter engages a record sheet lying beneath the bill head; means for relieving the pressure of the pressure rollers on the bill head to permit removal of a 20 written bill; and means controlled by the pressure-relieving means and acting automatically upon release of the latter after removal of a bill, to throw the platen, with the record sheet, in counter-line-feed direction to a position where another bill 25 head may be fed into the machine without allowance of space on the record sheet for display and similar matter on the bill head.

8. In a typewriting machine; a revolute 30 platen; pressure rollers and paper clutching fingers coöperating with the platen to hold paper to the latter, the pressure rollers being within the margins defined by the paper fingers so that the former may engage a bill 35 head or the like which is free from the latter, while the latter engages a record sheet lying beneath the bill head; means for relieving the pressure of the pressure rollers on the bill head to permit removal of a written bill; 40 means controlled by the pressure-relieving means and acting automatically upon release of the latter after removal of a bill, to throw the platen, with the record sheet, in counter-line-feed direction to a position 45 where another bill head may be fed into the machine without allowance of space on the record sheet for display and similar matter on the bill head; and means for thereafter driving the platen with record sheet and 50 new bill head to a position for properly printing on the latter.

9. In a typewriting machine; a revolute platen; pressure rollers and paper clutching fingers coöperating with the platen to hold 55 paper to the latter, the pressure rollers being within the margins defined by the paper fingers so that the former may engage a bill head or the like which is free from the latter while the latter engages a record sheet 60 lying beneath the bill head; means for relieving the pressure of the pressure rollers on the bill head to permit removal of a written bill; means controlled by the pressure-relieving means and acting automatically 65 upon release of the latter after re-

moval of a bill, to throw the platen, with carbon and record sheet in counter-line-feed direction to a position where another bill head may be fed into the machine without allowance of space on the record sheet for 70 display and similar matter on the bill head; and means for thereafter driving the platen with record sheet and new bill head to a position for properly printing on the latter, said backward and forward driving means being normally disconnected from the platen. 75

10. In a typewriting machine; a revolute platen; pressure rollers and paper clutching fingers coöperating with the platen to hold paper to the latter, the pressure rollers being within the margins defined by the paper fingers so that the former may engage a bill head or the like which is free from the latter while the latter engages a record sheet lying beneath the bill head; means for relieving the pressure of the pressure rollers on the bill head to permit removal of a written bill; means controlled by the pressure-relieving means and acting automatically upon release of the latter after removal 90 of a bill, to throw the platen, with the record sheet in counter-line-feed direction to a position where another bill head may be fed into the machine without allowance of space on the record sheet for display and similar matter on the bill head; means for 95 thereafter driving the platen with record sheet and new bill head to a position for properly printing on the latter, said backward and forward driving means being normally disconnected from the platen; and means for automatically disconnecting both of said driving means from the platen when the new bill head has arrived at printing position. 100

11. In a typewriting machine, the combination with a rotary platen, of a motor to rotate the platen, means for normally holding the motor at rest under tension and disconnected from the platen to permit the latter to be rotated independently of the motor, 105 a motor-control key operable to release the motor, and means operated by said motor to effect a driving connection thereof with the platen. 110

12. In a typewriting machine the combination with a rotary platen, of pressure rolls to bear against the platen and hold a work-piece thereon, a motor, means to normally hold the motor at rest and under tension, a controlling key, and means operated by the 115 key when depressed to release the pressure rolls from the platen, said key operable when released to effect a return of the pressure rolls to the platen, said key also operable when released to effect a driving connection 120 between the motor and the platen whereby the platen is driven by the motor. 125

13. In a typewriting machine the combination with a rotary platen, of pressure rolls to bear against the platen and hold a work- 130

piece thereon, a motor, means to normally hold the motor at rest and under tension, a controlling key, means operated by the key when depressed to release the pressure rolls 5 from the platen, said key operable when released to effect a return of the pressure rolls to the platen, said key also operable when released to effect a driving connection between the motor and the platen whereby 10 the platen is driven by the motor, a stop to limit the platen-driving movement of the motor, a crank connected to the motor for returning the latter, and a stop to limit the return movement of the motor, the motor- 15 holding means being automatically reset to hold the motor as the latter is returned to its normal position of rest.

14. The combination with a rotary platen, of means for holding a record sheet thereon, 20 additional means for holding on the platen a work-sheet overlying the record sheet, a motor normally held under tension and disconnected from the platen to permit the platen to rotate independently thereof, and 25 a controlling key manually operable in one direction to release said additional holding means from the work-sheet to permit it to be withdrawn from the machine, while the said record sheet is held on the platen, said controlling key operable in the reverse direction 30 to release the motor and effect a driving connection between the motor and platen for rotating the latter.

15. The combination with a rotary platen, 35 of means for holding a record sheet thereon, additional means for holding on the platen a work-sheet overlying the record sheet, a motor normally held under tension and disconnected from the platen to permit the platen to rotate independently thereof, a 40 controlling key manually operable in one direction to release said additional holding means from the work-sheet to permit it to be withdrawn from the machine, while the 45 said record sheet is held on the platen, said controlling key operable, when released, to restore said work-sheet-holding means and concomitantly effect a driving connection of the motor to the platen and cause the platen 50 to be rotated by the motor and a stop to determine the extent of rotation of the platen by the motor.

16. In a typewriting machine, the combination with a rotary platen, of feed rolls to 55 bear against a work-sheet on the platen, work-holding means arranged to engage the margins of an underlying record sheet extending laterally beyond said work-sheet, a motor to rotate the platen, a trip device to 60 normally hold the motor at rest under tension and disconnected from the platen, and a key operable, when depressed, to release said feed rolls from the platen and permit said work-sheet to be withdrawn while the 65 underlying record sheet is held by its hold-

ing means, said key operable, when released, to effect a return of the feed rolls to holding position, said key also controlling said trip device and operable concomitantly with the return of the feed rolls, to release the motor 70 and effect a driving connection between the motor and the platen, whereby the platen is rotated by the motor.

17. In a typewriting machine, the combination with a revoluble platen, of a spring 75 motor, means to normally hold the motor at rest under an operating tension and disconnected from the platen to permit the platen to rotate independently thereof, means to release the motor at will from said holding 80 means, means to enable the motor to connect itself to the platen and drive the latter in counter-line-feed direction from the position it occupies at the time of connecting the motor thereto, adjustable means for arresting 85 the platen after a variable predetermined throw of the latter by the motor, a crank for revolving the platen in the reverse direction, and retensioning the motor, and means for arresting the crank after such reverse movement of the platen in excess of its forward throw by the motor, and for disconnecting the motor from the platen and restoring it to the control of said holding means. 90

18. In a typewriting machine, a revoluble 95 platen, a crank loose on the axle thereof, a normally inactive motor connected to the crank and normally under a driving tension, restraining means for said motor, means for releasing the motor and crank, and means 100 to enable the crank to connect itself to the platen to drive the same under the tension of said motor, said connecting means including a toothed wheel fast to the platen, a dog on the crank for engagement with the toothed 105 wheel, and tripping mechanism for causing the dog to engage and disengage the toothed wheel.

19. In a typewriting machine, a revoluble platen, a crank loose on the axle thereof, a 110 normally inactive motor connected to the crank and normally under a driving tension, restraining means for said motor, means for releasing the motor and crank, means to enable the crank to connect itself to the platen 115 to drive the same under the tension of said motor, said connecting means including a toothed wheel fast to the platen, a dog on the crank for engagement with the toothed wheel, and tripping mechanism for causing 120 the dog to engage and disengage the toothed wheel, and means for automatically restoring the crank and motor to the control of said restraining means when they are disengaged from the platen. 125

20. In a typewriting machine, a revoluble platen, a crank loose on the axle thereof, a normally inactive spring motor connected to the crank, releasable means for restraining the crank and motor, a toothed wheel 130

- fast to the platen, a dog on the crank for engagement with the toothed wheel, tripping mechanism for causing the dog to engage and disengage the toothed wheel, and means 5 for automatically operating the trip to disengage the crank and platen after a return movement of the latter in excess of its forward movement, and for restoring it to the control of said releasable means.
- 10 21. The combination with a revoluble platen and feeding devices to engage the side edges of the record sheet, of a main feed roll, a release key therefor, a normally disconnected platen-returning spring, means normally restraining said spring, means controlled by said key to release said restraining means upon the release of said key, and automatic means to connect said spring to the platen to drive the same.
- 15 22. The combination with a revoluble platen and feeding devices to engage the side edges of the record sheet, of a main feed roll, a release key therefor, a normally disconnected platen-returning spring, means 20 normally restraining said spring, means controlled by said key to release said restraining means upon the release of said key, and automatic means to connect said spring to the platen to drive the same.
- 25 23. The combination with a revoluble platen and feeding devices to engage the side edges of the record sheet, of a main feed roll, a release key therefor, a normally disconnected platen-returning spring, means 30 normally restraining said spring, means controlled by said key to release said restraining means upon the release of said key, automatic means to connect said spring to the platen to drive the same, and a manually-operable device to return said platen and re-tension said spring.
- 35 24. The combination with a revoluble platen and feeding devices to engage the side edges of the record sheet, of a main feed roll, a release key therefor, a normally disconnected platen-returning spring, means normally restraining said spring, means controlled by said key to release said restraining means upon the release of said key, automatic means to connect said spring to the platen to drive the same, a manually-operable device to return said platen and re-tension said spring, and means to enable said spring to become automatically disconnected 40 from the platen and restored to the control of said restraining means.
- 45 25. The combination with a revoluble platen and feeding devices to engage the side edges of the record sheet, of a main feed roll, a release key therefor, a normally disconnected platen-returning spring, means normally restraining said spring, means controlled by said key to release said restraining means upon the release of said key, automatic means to connect said spring to the platen to drive the same, and a manually-operable device to return said platen and re-tension said spring.
